UNITED STATES PATENT OFFICE.

WILLIAM LOUIS HALEY, OF BELTON, TEXAS.

MOTOR.

SPECIFICATION forming part of Letters Patent No. 391,412, dated October 23, 1888.

Application filed June 2, 1888. Serial No. 275,882. (No model.)

To all whom it may concern:

Be it known that I, WILLIAM LOUIS HALEY, a citizen of the United States, residing at Belton, in the county of Bell and State of Texas, 5 have invented a new and useful Improvement in Motors, of which the following is a specification.

My invention relates to improvements in motors; and it consists in certain novel features hereinafter described and claimed.

In the accompanying drawings, Figure 1 is a front view of my improved device, and Figs. 2 and 3 are side views of the same, looking at the opposite sides thereof. Fig. 4 is a plan 15 view of the device. Fig. 5 shows a modification, and Fig. 6 is a detail view showing the connection between the parts of the detachable standard.

Referring to the drawings by letter, A designates the main standard, consisting of the detachable sections *a* *b*. The section *a* is provided near its upper end with a transverse perforation, *e*, through which I insert a bolt, *B*, screw-threaded at both ends, on which I 25 mount the nuts *C*, which are adapted to turn up against the sides of the standard. To the opposite sides of the upper section, *b*, of the standard, at the lower end of the same, I secure the metallic plates *D*, which are provided in 30 their lower ends with the notches or open slots *d*. The plates pass down on opposite sides of the lower section, the notches fitting over the ends of the bolt *B*, and the nuts are then turned home, thus firmly securing the two sections 35 together. The lower section, *a*, is provided with a journal-box, *E*, on its upper end, and a notch, *F*, is formed in the lower end of the upper section to fit over said journal-box.

G designates a short standard similar in 40 size and shape to the lower section, *a*, of the standard *A*, and arranged at a slight distance from the same.

To the lower ends of the standards *A* *G*, I 45 secure the socket-fastenings *I*, in which are secured the upper ends of the supporting-feet *H*, as shown. On the upper end of the standard *G*, I provide a journal-box, *g*, and in the said journal-box and the journal-box *E*, I mount the transverse shaft *I*, having a sprocket- 50 pinion, *J*, on one end and a crank-arm, *K*, on the other end. A grindstone, *L*, is mounted centrally on this shaft and is driven thereby.

M designates a trough, which is hung loosely on the shaft *I*, and is provided on one side, at or near its straight edge, with the keepers *N*, 55 which are adapted to be engaged by a sliding bolt, *O*, mounted on an arm, *P*, extending horizontally from the standard *G*. This trough, when arranged as shown in full lines, is adapted to hold water to prevent overheating of the 60 grindstone, as will be readily understood, and when arranged as shown in dotted lines in Fig. 2 serves as a cover to prevent grease and dirt falling upon the grindstone. At the outer end of the arm *P*, I provide an adjustable bearing consisting of the sleeve *Q* and the slotted strap or plate *R*, extending therefrom. The slotted plate *R* rests upon the arm *P*, and a set-screw, *S*, is inserted vertically through the slot in the plate and through the arm, thus 65 securing the bearing at any desired point. In this bearing I journal a short shaft, *T*, having a sprocket-wheel, *U*, on one end and a crank-arm, *V*, on the other end. The sprocket-wheel is connected to the sprocket-pinion *J* by an 70 endless sprocket-chain, *W*, as shown.

On the side of the upper section, *b*, of the standard *A*, I provide the horizontal arms *Y*, in the free ends of which I mount the reciprocating rod or bar *Z*, which is connected to the 80 crank-arm *K* by a pitman, *z*, as shown. The dasher-staff *y* is adjustably secured within a thimble, *x*, by a set-screw, *w*, as shown, and the said thimble is carried by the reciprocating rod or bar *Z*, which is adjustably secured within 85 a thimble, *3*, carried by the bar or rod *Z*. The crank-arm *V* is intended to be connected to a suitable treadle when it is desired to operate the device by foot-power; but for all ordinary purposes it will be sufficient to impart motion 90 to the machine by a crank-handle on the sprocket-wheel.

From the foregoing description, taken in connection with the accompanying drawings, it will be seen that I have provided a very simple and compactly-arranged device, by means of which the churn or grindstone may be easily and rapidly operated. The several parts, being made readily detachable, can be easily separated for the purposes of repairs and cleaning, and can be also stored in a small compass for transportation.

When so desired, one of the standards may be dispensed with, and the remaining standard

provided with four supporting-feet, so as to be held upright. In this case the grindstone will be dispensed with and a cast-iron balance or fly wheel, J', will be substituted for the crank-arm K, the reciprocating rod being secured to the fly-wheel. This modified arrangement is shown in Fig. 5.

It will be observed that the grindstone acts as a balance-wheel for the churn, so that it will run smoothly and evenly.

The dasher-staff can be quickly and easily adjusted to the height of the churn-body and the quantity of cream therein by means of the thimbles and set-screws, as will be readily understood.

Having thus described my invention, what I claim, and desire to secure by Letters Patent, is—

1. The combination of the section a, the bolt 20 inserted transversely through the same and having its ends projected beyond the sides of the said section, the section b, the plates secured to said section b and having their lower ends notched and fitting over the ends of the bolt in the section a, and the nuts mounted on said bolt and bearing against said plates, as set forth.

2. The combination of the standard-section a, the section b, detachably secured upon the 30 section a, the arms projecting from the section b, the reciprocating rod Z, mounted in said arms and carrying a thimble, the rod 2, se-

cured in said thimble and provided at its lower end with a thimble, X, the dasher-staff adjustably secured in said thimble X, the driving-shaft having a crank-arm, and the connecting-rod between said crank-arm and the reciprocating rod, as set forth.

3. A motor adapted to operate a churn, comprising the standard-section a, the standard G, 40 erected to one side thereof, the transverse shaft supported by the standard G and the standard-section a, and having a crank-arm at one end connected to the churn, a pinion mounted on the opposite end of said shaft, an arm extending horizontally from the standard G, and the driving-shaft mounted on said arm and geared to said pinion, as set forth.

4. In a motor for operating churning and grindstones, the combination, with the standards, of 50 the transverse shaft supported thereby, carrying the grindstone and connected to the churn, gearing for rotating said shaft, and the trough hung on said shaft and adapted to cover the grindstone when the same is acting as a fly-wheel for the churn, as set forth.

In testimony that I claim the foregoing as my own I have hereto affixed my signature in presence of two witnesses.

WILLIAM LOUIS HALEY.
